Specification for Design.

Patented June 15, 1920.

Application filed September 19, 1919. Serial No. 325,020. Term of patent 14 years.

To all whom it may concern:

Be it known that I, MARThA V. BAUER, a citizen of the United States of America, residing at Washington, District of Columbia, have invented a new, original, and ornamental Design for a Friendship-Token, of which the following is a specification, reference being had to the accompanying drawing forming part thereof.

In the drawing, the view represents a front elevation of a friendship token showing my design.

I claim:

The ornamental design for a friendship token, as shown.

MARThA V. BAUER.
